THE NORRIS PETERS CO., PHOTO-LITHO., WASHINGTON, D. C.

UNITED STATES PATENT OFFICE.

MYRON L. WINANS, OF WACO, TEXAS.

WAGON-BODY.

SPECIFICATION forming part of Letters Patent No. 683,828, dated October 1, 1901.

Application filed February 28, 1901. Serial No. 49,318. (No model.)

To all whom it may concern:

Be it known that I, MYRON L. WINANS, a citizen of the United States, residing at Waco, in the county of McLennan and State of Texas, have invented certain new and useful Improvements in Wagon-Bodies; and I do hereby declare the following to be a full, clear, and exact description of the invention, such as will enable others skilled in the art to which it appertains to make and use the same.

My invention relates to improvements in wagon-bodies, such as may be placed upon any suitable running-gear, and by the use of my said invention one wagon may be employed to accomplish the work ordinarily requiring the services of several different styles of wagons, as will hereinafter appear.

In order to more fully describe my said invention, reference is had to the accompanying drawings, in which—

Figure 1 is a perspective view of a wagon embodying my said invention. Fig. 2 is a side elevation of the same, showing the wagon-body tilted and the rear gate lowered ready to load stock. Fig. 3 is a central vertical section through a wagon equipped with my improvements, the same being adapted for loading hay and the like. Fig. 4 is a side elevation showing the side or rack bars closed and the end-gates in an upright position, the wagon being adapted to carry loose material. Fig. 5 is a front perspective view of the front end-gate, showing the detachable windlass; and Fig. 6 is a similar view in detail, showing the automatic gravity-latch carried by the front bolsters.

In the accompanying drawings similar parts are indicated by the same letters of reference throughout the several views.

A represents the wagon-body, mounted upon the bolsters B B' of the running-gear x, mounted upon the wheels X, which may be of any suitable or desirable type. This body A is composed of the floor a, supported by the bolsters B B', and the side base-boards a' a', said floor and base-boards being held together by the bottom strips a².

A' A² are the front and rear end sills, respectively, which are held fastened to the base part of the body, such as by means of the through-bolts a³. A³ represents perforated angle-irons secured to the upper side

of each of these end sills A' A², the purpose of which will hereinafter appear.

C C are detachable side-boards adapted to be placed above the base-boards a'. c c are posts or uprights adapted to be inserted into the sockets a⁴ upon the base-boards a', thereby holding said side-boards securely in position. Secured to the tops of these posts are the upsetting brackets c'. Fitting into these brackets c' are the stakes D, which support the regularly-spaced bars or racks E in such a manner that when said stakes D occupy an oblique position (see Fig. 4) the bars E will close up and rest one upon another.

F is the front end-gate, comprising the two uprights f f' and the front board f², which will be on a level with the side-boards C C, and the cross-bars f³, joining the uprights f f'. f⁴ is a cross-bar located in front of the front board f², provided with the vertical openings f⁵ f⁶. f⁶ is a central upright, resting upon the cross-bar f⁴, provided at its upper end with the slot f⁷, adapted to receive a rope. G G are metal straps running from top to bottom of said side uprights f f', said straps being spaced from said uprights, so as to pass over the ends of the side-boards. g represents a pin passing through these straps G and secured to each of the uprights f f', the purpose of these pins being to hold said strap at the proper distance from the said uprights. g' g' are hooks upon the lower ends of each of these uprights f f'. H represents a windlass detachably mounted in the lower end of said end-gate, having a rope H' adapted to be wound thereon, and H² is a hook carried thereby. h represents holes passing through said windlass, adapted to receive a rod. h' is a ratchet-wheel securely fastened to said windlass and having the pawl h², adapted to engage therewith. This windlass is held in position upon the uprights f f' by means of the plates h³ h⁴, respectively. This plate h³ is slotted, so as to enable the removal of said windlass by swinging one end of said plate to one side, thereby releasing that end of the windlass.

P represents the rear end-gate, substantially a duplicate of the front end-gate, omitting the windlass. When the rear end-gate is lowered, the sill A² is removed from its place in the bottom of the wagon-body and

placed in this opening at the end of the gate adjacent the wagon to cover the opening.

5 J is a latch pivotally secured upon each of the uprights of the bolster B, as by the pivot-pin j. This latch normally rests in the position shown in dotted lines, as indicated by J', Fig. 6.

I represents a catch mounted to turn in the bolster B and engage in the recess j' of the latch J, thereby holding the same in an upright position. Upon releasing this catch I the latch J will drop down and is securely held in a horizontal position by means of the rest K.

15 L are pins which are adapted to enter the apertures f⁴ f⁵ and through the angle-irons A³, and thereby hold the front end-gate in an upright position, or when the end-gates swing outwardly they are held in any desired 20 position by the pins L being inserted in the holes M of the base-boards, said pins abutting against the pins g upon the end-gate. The lower ends of the end-gates are held in place by the hooks g' thereon engaging with 25 the tie-rods O beneath the wagon-body, it being impossible to remove the end-gates until considerably lowered, thus preventing accidental displacement of the same. When the windlass is used, these pins are inserted 30 in the holes h, thereby providing means for turning the same. The pins L' are adapted to hold the rear gate in the same manner as the front end-gate.

N represents through or tie bolts adapted 35 to be passed through the outer metal straps G, side-boards C, and end-gates when the sides are upon the wagon, these tie-bolts tending to hold the same rigid and solid.

The wagon, as shown in Fig. 1, is equipped 40 for carrying its bulkiest load and also for carrying stock, the rack or side bars being elevated and spaced apart and the end-gates in their uppermost positions. In Fig. 2 the wagon-body is tilted upwardly, the front part 45 of the same being supported by the latches J J, which automatically engage the wagon-body on each side when the same is lifted to the proper height. The rear end-gate is also lowered and the rope H' of the windlass is 50 brought into use when loading live or dead stock. When used in this manner, the rear end sill A² is removed from the base of the body and is utilized for the purpose of closing the opening left in the end-gate when lowered. When the wagon has been loaded, the rear end-gate is raised, the tie-bolt N is passed 55 through the gate and wagon sides, the sill A² is restored to its proper position, and the front end of the wagon-body is lowered upon the bolster B. This is accomplished by raising the latch J to an upright position and fastening the same by the catch I, the wagon-body then being free to descend. In Fig. 3 the same wagon is shown equipped as a hay-wagon. This is done by removing the side boards C and rack-bars E from the sides of the wagon, which is accomplished simply by

lifting the side posts c out of their sockets a¹. The front and rear end-gates are given an overhang, the angle of which may be adjusted by means of the pins L L' being inserted in the holes M, thereby securing said gates in any desired position. Through the slot f⁷ is passed the rope H' of the windlass H, the end of said rope being secured to the top of the rear end-gate. This rope is passed over the load and the windlass turned until the rope becomes tight, said rope being held tight by the pawl engaging the ratchet n' upon the said windlass. In this way it is possible to carry enormous loads upon the wagon without the same spilling or breaking. For ordinary run-about purposes the end-gates are both removed, leaving the base part of the body only. These end-gates are removed by swinging the same to their lowermost position and then lifting the hooks g', carried upon the ends thereof, from the rod O, as will be readily seen. When hauling sawed wood, the end-gates are preferably secured 90 in an upright position by passing the pins L L' through the end-gates and through the angle-irons A³ A³. Should it be desired to remove the windlass from the wagon, the retaining-plate h³ is swung outwardly, as before explained, thereby releasing that end of the windlass, permitting it to be readily removed.

Fig. 4 shows the wagon equipped for carrying loose loads, such as grain, dirt, and the like. This transformation is made by swinging the upper ends of the stakes D forward, thereby closing the rack-bars E, so as to rest upon each other. The rear end-gate is then raised so as to occupy an upright position, the tie-rod N being passed through the same to retain it in position.

It is obvious that although I have shown only several different kinds of wagons into which my invention enables a single wagon to be transformed it is obvious that many additional uses will suggest themselves to any one familiar with this class of wagons. It is also obvious that many changes might be made in the details of the same without departing from the spirit of my said invention; but

What I claim, and desire to secure by Letters Patent of the United States, is—

1. In a wagon, the combination with the wagon-body; of front and rear end-gates, means for adjustably securing the same at any desired inclination, and a windlass carrying a rope, mounted in said front end-gate, substantially as described.

2. In a wagon, the combination with the wagon-body, adapted to have its front end elevated; of a bolster carried by the running-gear, and a latch upon said bolster, adapted to keep the same in an elevated position, substantially as described.

3. In a wagon, the combination with the wagon-body; of detachable side-boards carried thereby, and spaced rack-bars mounted

above said side-boards, said rack-bars being adapted to be closed up, substantially as described.

4. In a wagon, the combination with the wagon-body; of front and rear end-gates pivotally mounted upon said wagon-body, perforated extensions upon said wagon-body, and pins adapted to be inserted in said perforations, and hold said gates at any desired position, substantially as described.

5. In a wagon, the combination with the wagon-body; of an end-gate therefor, means for detachably securing the same to said wagon-body, means for securing said gate in an upright position, and means for holding said gate at any desired inclination, substantially as described.

6. In a wagon, the combination with the wagon-body; of a bolster adapted to support said wagon-body, and a latch carried by said bolster adapted to automatically drop into position and support said wagon-body when the same has reached a predetermined height, substantially as described.

7. In a wagon, the combination with the wagon-body; of a front end-gate having means for detachably securing the same to the wagon-body, and a detachable windlass carried thereby, substantially as described.

8. In a wagon, the combination with the wagon-body, and a bolster for supporting the same; of a latch pivoted upon said bolster, having a recess formed therein, a rest for supporting said latch when in a horizontal position, and a catch adapted to engage in said recess and retain said latch in an upright position, substantially as described.

9. In a wagon, the combination with the wagon-body, detachable side-boards carried thereby, and brackets at intervals near the tops of said side-boards; of spaced rack-bars adapted to be mounted above said side-boards, and stakes supporting said rack-bars, adapted to be inserted in said brackets, substantially as described.

10. In a wagon, the combination with the wagon-body; of a rack adapted to be carried upon the top of said body, having a plurality of rack-bars spaced at regular intervals, and stakes pivotally secured to said rack-bars, whereby when said stakes rest at an oblique angle to said bars, the spaces between said bars are closed, substantially as described.

11. In a wagon, the combination with the wagon-body, and cross-rods secured beneath said body at each end thereof; of a front and rear end-gate, and hooks upon the bottoms of said end-gates adapted to engage with said cross-rods, substantially as described.

12. In a wagon, the combination with the wagon-body adapted to have its front end elevated; of a bolster carried by the running-gear, and a device carried by said bolster adapted to automatically drop into place and hold said wagon-body in an elevated position, substantially as described.

In testimony whereof I affix my signature in presence of two witnesses.

MYRON L. WINANS.
